US00D762168S

(12) **United States Design Patent**
Sandoval et al.

(10) **Patent No.:** **US D762,168 S**
(45) **Date of Patent:** ** Jul. 26, 2016

(54) **MOBILE POWER DEVICE**

(71) Applicant: **Cobra Electronics Corporation**,
Chicago, IL (US)

(72) Inventors: **Ramon Sandoval**, Chicago, IL (US);
Wilfred Charles Boudreau, Mundelien,
IL (US); **Christopher Steven deWaal**,
Oakwood Hills, IL (US); **Jonathan
Charles Levell**, Evanston, IL (US);
Jeffrey Patrick Heuel, Elmhurst, IL
(US)

(**) Term: **15 Years**

(21) Appl. No.: **29/535,785**

(22) Filed: **Aug. 10, 2015**

(51) LOC (10) Cl. **13-02**
(52) U.S. Cl.
USPC **D13/107**

(57) **CLAIM**

The ornamental design for a mobile power device, as shown and described.

DESCRIPTION

FIG. 1 is a perspective view from the top-left of the mobile power device;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines in the drawings illustrate elements of the mobile power device which form no part of the claimed design.

1 Claim, 5 Drawing Sheets
